UNITED STATES PATENT OFFICE.

JAMES FRANCIS McNULTY, OF LOS ANGELES, CALIFORNIA.

ICE-CREAM-DISPENSING DEVICE.

1,364,569.

Specification of Letters Patent.

Patented Jan. 4, 1921.

Application filed May 28, 1919. Serial No. 300,426.

To all whom it may concern:

Be it known that I, JAMES FRANCIS McNULTY, a citizen of the United States, residing at Los Angeles, in the county of Los Angeles and State of California, have invented new and useful Improvements in Ice-Cream-Dispensing Devices, of which the following is a specification.

My invention relates to a vending machine and more particularly to a vending machine of the coin-in-slot operating type.

The principal object of my invention is to provide a vending machine in which small bricks of ice cream may be kept in a solid state and delivered one by one as coins are inserted in a slot and a handle operated.

With this and other objects in view, my invention consists in the construction, combination and arrangement of parts herein-
20 after described and claimed.

In the accompanying drawings which form a part of this specification,

Figure 1 is a view in side elevation of an ice cream vending machine embodying
25 the principles of my invention.

Fig. 2 is an enlarged longitudinal vertical section of the machine shown in Figs. 1 and 3 taken on line 2-2 in Fig. 3.

Fig. 3 is a view in front elevation of a pair of machines, the side elevation of which is shown in Fig. 1, seen in the direction indicated by arrow 3 in Fig. 1.

Fig. 4 is a vertical sectional view on the line 4-4 of Fig. 2, the section plane being
35 at right angles to the view shown in Fig. 2.

Fig. 5 is a transverse section on the line 5-5 of Fig. 4 showing the coin slot and associated controlling and operating parts.

Fig. 6 is a sectional detail on the line
40 6-6 of Fig. 4 further showing the coin operating mechanism in its relation to the locking device.

Referring more particularly to the several figures and the reference numerals, 10 is a casing which serves as a housing for the operating parts of the machine and is adapted to be mounted on a pedestal or other support. An inverted vacuum-jacketed container 11 is screwed into an opening in the top of casing 10 so that its mouth extends downwardly into the chamber 12 formed by casing 10. A horizontal transverse shaft 13 having a crank 14, fixed on its outer end, outside the casing, and a concentric disk 15 fixed on its inner end, within the casing, has its outer end journaled in the casing

wall 16, while its inner end is journaled in a standard 17 fixed to the floor of the casing. An eccentric disk 18 is fixed on the middle of the shaft. A slotted bar 19 embracing the shaft 13 so that the shaft turns within its slot extends upwardly from the shaft and supports a platform or table 20 upon which the column of ice cream bricks normally rests. This table also serves as a stopper for the container and therefore has its upper surface covered with a veneer 21 of cork provided with a rubber washer 21', the latter serving to hermetically close the container opening and the former serving as a heat insulator. A short bar 22 is fixed to the under side of the platform and extends downwardly parallel to the slotted bar 19 leaving a space 23 between the bars centrally positioned with respect to the table. 75 Two pairs of links 24 and 25, each pair having its ends connected to the parallel bars 19 and 22 by pivot pins 26 and 27 respectively, have their other ends pivotally connected to an upright 28, rising from the floor of the casing, by pivot pins 29 and 30.

A roller 31 is fixed between the parallel bars 19 and 22 at the lower end of the short bar and the second roller 32 is pivoted to the lower end of the slotted bar 19. These 85 rollers are in position to engage the edge of the eccentric disk 18 which operates as a cam between them as the shaft turns. A roller 33 is fixed to the outer face 34 of the eccentric disk by a pivot pin 35. A pair of 90 radial arms 36 and 37 having bearings on their inner ends which turn on the shaft 13 have fixed to their outer ends a common rim segment 38 concentric with the shaft 13. This rim segment serves as a retaining support for the ice cream bricks when the machine is operated as will presently appear. Formed integral with the bearing of one of the radial arms 37 are two radial fingers 39 and 40 so placed that the third roller 33 100 is positioned between them. A helical spring 41 coiled around shaft 13 has one end 42 fixed in the casing and the other end 43 fixed in the shaft. This spring is arranged to wind up as the crank is turned and serves to return the shaft and crank to their normal positions. The concentric disk 15 has a hole 44 drilled through it in position to receive a detent pin 45 formed integral with a slide bar 46, the opposite end of which is 110 recessed to receive a helical spring 47 which acts under compression to hold the bar and

pin against the disk. The slide bar 46 and actuating spring 47 are mounted in the standard 17.

Side bar 46 is also provided with a vertical recess 48 formed in its side to receive the coin. A horizontal lever shaft 49 having one end extending outwardly through the side casing has an exterior lever 50 fixed to its outer end, its inner end being journaled in the upper part of standard 17. An inner lever 52 fixed to the lever shaft 49 adjacent the standard has a right angled finger 53 projecting through a slot 54 formed in a retaining plate 55 screwed to the supporting standard 17 to hold the slide bar 46 in place. The finger 53 of the lever 52 extends across a slot space 56 between the slide bar retaining plate 55 and the standard wall 57, this wall being milled out to form a coin slot 20 and a seat for the slide bar. An external coin slot 58 is cut in the top of the casing in vertical alinement with slot space 56 and coin recess 48 in the slide bar. A coin releasing cam 59 is fixed on the face of the concentric disk 15 adjacent the standard in position to engage the detent pin 45 as the disk 15 revolves. Stop pins 60 and 61 are fixed in the side of the casing to limit the motion of the operating handle 14, and stop pins 62 and 63 are similarly fixed to limit the motion of the coin controlling lever 50.

A receiving chamber 64 opening upward within the casing in position to receive the bricks of ice cream as they are delivered from the container is formed by a partition 64' in the front part of the casing chamber 12. A trap door 65 opening outwardly from the chamber is hinged to the front of the casing. A coin box 66 having a door 67 adapted to be locked by a padlock 68 is fixed to the side of the machine under the slot on the side of the machine opposite to the crank.

A pet cock 69, to which an air pump may be attached, is fixed in the side of the container 11 to provide for exhausting the air from the vacuum jacket. Vertical guide walls 70 and 71 between which the bricks of ice cream loosely fit are fixed within the container. A lug 72 formed on the lower end of the container casing is adapted to operate with a similar lug 73 fixed to the top of the machine casing, said lugs being provided with holes 74 through which a padlock 75 may be fixed to lock the container and the casing together and prevent the removal of the container from the casing by unauthorized persons.

Operation: The container, having had the air completely exhausted from its vacuum chamber, is filled with hard frozen ice cream bricks and screwed into place on the casing. A coin is now inserted through the outer coin slot 58 until it passes into the slot space 56. The lever 50 is then turned whereupon

the finger 53 engages the upper edge of the coin and forces it down into the coin recess 48 in the slide bar 46. The coin recess 48 in the slide bar being in such a position that as the coin is forced into it, its edge engages 70 the edge of the coin recess and operates to further compress spring 47 and to withdraw the detent pin 45 from the disk 15, thus unlocking the operating parts of the machine. The handle 14 is then pulled down in the 75 direction indicated by arrow a. This turns the shaft 13 and with it the concentric disk 15 and the eccentric disk 18 at the same time increasing the tension of the restoring spring 41. As the eccentric disk 18 turns about 80 the shaft, the roller 31 resting upon its edge follows it and the supporting table with the ice cream upon it is lowered to the position indicated by the dotted lines in Fig. 2. As the eccentric disk turns, the roller 33 fixed 85 in its side comes into engagement with the finger 39 causing it and the radial arms 36 and 37 to turn about the shaft until the retaining plate or rim segment 38 moves into the position indicated in dotted lines in Fig. 90

2. The arrangement is such that the retaining plate 38 is brought under the container when the table has moved downwardly a distance approximately equal to the thickness of an ice cream brick. As the 95 retaining plate moves into the position indicated its free end engages the lowered brick and as the movement is completed shoves it off of the supporting table into the delivery chamber 64. The remaining bricks 100 are supported by the retaining plate until the handle is released and the spring operates to turn the shaft and the attached parts back to their normal position, whereupon the retaining plate is withdrawn by the action of roller 33 upon finger 40 and the supporting table returns to its normal position supporting the remaining bricks and closing the container. As the locking disk 105 110 turns on its axes in the operating movement, the cam 59 is brought into engagement with the detent pin 45 forcing it outward against the spring 47 sufficiently to release the coin and allow it to drop into the coin box below. In the returning movement 115 as the cam 59 moves away from the end of the detent pin 45, the latter presses against the face of the disk until its normal position is reached, whereupon it is thrust into the hole 44 by the action of the spring 47, thus locking the apparatus against movement until another coin is inserted. It is evident that as the cam disk 18 turns to a diametrically opposite position from the normal one, its edge comes into engagement with the 125 lower roller 32 on the supporting bar 19, and operates to pull down the supporting table in case the weight alone is insufficient to actuate it.

Though I have shown and described my 130

machine as used for vending ice cream, it is evident that it may be used for vending other articles similar in form to an ice cream brick.

5 While I have shown the preferred construction of my ice cream vender as now known to me, it will be understood that various changes in construction and combination of parts may be made by those skilled 10 in the art without departing from the spirit of my invention as claimed.

I claim:

1. An ice cream vending machine comprising a casing; a thermally insulated container fixed into said casing and opening 15 downwardly thereinto; a receiving chamber; a movable closure for said container; and coin controlled means for withdrawing ice cream bricks one by one from said container and delivering the withdrawn bricks into said receiving chamber; said means including a shaft; a cam fixed to said shaft in operative relation to said closure; and a retaining and ejecting plate, pivotally connected to said shaft in co-operative relation with said closure to withdraw bricks of ice cream one by one from said container and deliver them into said receiving chamber.

2. An ice cream vending machine comprising a casing; a vacuum-jacketed container opening downwardly into said casing; a movable closure for said container; a shaft; a cam fixed to said shaft in operative relation to said movable closure; arms 30 pivoted on said shaft; a retaining plate fixed to said arms in co-operative relation with said closure; fingers pivotally con-

nected to said shaft in fixed relation to said arms; a pivoted roller fixed to said cam in operative relation to said fingers; and coin 40 controlled means for unlocking said shaft and allowing it to be operated.

3. An ice cream vending machine comprising a casing; a vacuum-jacketed container fixed into said casing and opening 45 downwardly thereinto; a closure which also serves as a supporting table; a slotted bar attached to the under side of said closure; a horizontal shaft extending through the slot in said slotted bar; an operating handle 50 fixed to said horizontal shaft; a cam disk fixed to said horizontal shaft; radial arms pivoted to the outer ends of said radial arms; radial fingers pivoted on said shaft in fixed 55 relation to said radial arms; a pivoted roller fixed into one face of said cam disk between said radial fingers; a pair of pivoted rollers fixed to said slotted bar in operative relation with said cam disk; a standard 60 fixed to the floor of said casing; parallel links pivotally connected to said slotted bar and said standard; a receiving chamber within said casing; a trap door opening into said receiving chamber; a coin controlling 65 means for normally locking said shaft but for unlocking said shaft when a coin is deposited therein and said means operated, and a spring adapted to return said shaft to its normal position after having been 70 operated.

In testimony whereof I have signed my name to this specification.

JAMES FRANCIS McNULTY.
